CLAIM

The ornamental design for a cassette for a video tape recorder, as shown and described.

DESCRIPTION

FIG. 1 is a bottom, rear and left side perspective view of a cassette for a video tape recorder showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and FIG. 8 is a top, front and right side perspective view thereof, shown with the front cover in an open position.

Fig. 1

*Fig. 2**Fig. 3**Fig. 4**Fig. 5**Fig. 6**Fig. 7**Fig. 8*
